ADJUSTABLE GENERATOR

Craig M. Snader, Rosedale, Pa.

Application August 8, 1945, Serial No. 609,671

5 Claims. (Cl. 171—252)

1

My invention relates broadly to multiple wave generators and more particularly to a precision type multiple wave generator which may be accurately adjusted to produce predetermined wave patterns at predetermined amplitude and phase.

One of the objects of my invention is to provide a simplified construction of multiple wave generator having means for accurately controlling the phase and amplitude of the generated wave.

Another object of my invention is to provide an improved construction of mechanical device for use in the generation of electric wave energy in which the amplitude and phase of the generated energy may be readily shifted from one condition to another.

A further object of my invention is to provide a construction of adjustable gear means which may be micrometrically adjusted to produce a highly precise wave form of predetermined characteristic.

Still another object of my invention is to provide a selective mechanism for electric generators for precisely determining the characteristics of electric waves including conditions of frequency, amplitude and phase.

Other and further objects of my invention reside in the construction of a multiple wave generator as set forth more fully in the specification hereinafter following by reference to the accompanying drawings in which:

Figure 1 is a plan view of the multiple wave generator of my invention showing the micrometric adjustment means associated therewith for controlling the characteristics of the output or wave form delivered by the multiple wave generator; Fig. 2 is a side elevational view of the multiple wave generator shown in Fig. 1; Fig. 3 is an end view of the multiple wave generator; Fig. 4 is a side elevational view of the multiple wave generator showing the coil support removed to illustrate the two coils employed in the circuit of the multiple frequency generator of my invention; Fig. 5 diagrammatically illustrates one application of the multiple frequency generator of my invention, and Fig. 6 diagrammatically illustrates a modified circuit embodying the multiple frequency generator of my invention in which the control windings are regeneratively coupled through the adjustable and angularly movable magnetic core structure.

The generator of my invention provides means whereby electric currents of predetermined frequency may be generated, combined and regulated so as to provide resultant currents having any desired characteristics as to frequency, amplitude and phase. The distinctive feature of my invention is the provision of adjustable mechanism in association with an electric current generator by which the frequency, amplitude or

2

phase or any or all of these features of the generated current may be varied at will to provide a resultant wave shape or characteristic curve produced by combining two or more such currents which is of predetermined pattern.

The mechanism by which the objects of my invention are carried out are set forth in the accompanying drawings in which a magnetic rotor or disc R is provided with a peripheral contour of such shape as will produce wave forms of predetermined characteristic. If a sine wave is to be produced the circumference of the disc is edged with small sine wave shapes. A saw-tooth generator curve characteristic is produced by edging the circumference of the disc with a saw-tooth pattern. The electric waves which are generated by the mechanism of my invention may be converted into sine waves or waves of other predetermined pattern by combining such waves with a predetermined wave pattern produced by another generator of the type embodying my invention. The rotor R having the predetermined pattern on the periphery thereof is driven by motor M controlled from suitable motor controller D interposed in circuit with the source of power supply. The rotor R has the periphery thereof driven in direct alignment and in front of the magnetized core C of the solenoid system S, current being induced in such solenoid system in the circuit A indicated in Fig. 2. The frequency of the generated current is the product of the rotor speed and the number of wave shapes R' on the periphery of the rotor R. The frequency can be changed by changing the speed of rotor R by adjusting motor controller D.

The magnetized core C is axially rotatable under control of micrometer mechanism 11 by which the magnetized core C may be advanced or retracted toward or away from the periphery of rotor R for changing the air gap between the end of the magnetized core C and the wave forms R' on the periphery of rotor R. The magnetized core C is provided with a screw threaded portion 17 which engages internal screw threads 18 in the bore of the transverse projection 19 on the plate member 20. The plate member 20 includes an end portion 21 in the form of a transversely extending sleeve or hub which is angularly adjustable on a cylindrical projection 22 formed on the standard 23 extending vertically from the base of the unit represented at 24. The standard 23 thus serves as a swivel support about which plate member 20 may be angularly adjusted and also has a journalling means for the shaft 25 which extends from motor M to rotor R. The plate 20 is provided at the end opposite the aforementioned pivoted end with a segmental gear 13. The segmental gear 13 includes transversely extending teeth which mesh with the worm gear 14 for adjusting the segmental gear 13 upwardly or

downwardly about the sleeve 22 as a center pivot. The worm gear 14 is carried by a vertical shaft 26 which is journalled in the lower end 27 adjacent the base 24 and the upper end 28 in bracket member 29. The upper end of shaft 26 projects through the bracket 29 and is engaged by the rotatable calibrated head 16. The rotatable calibrated head 16 may be gripped by a tool or manually by the fingers and revolved with respect to the indicator point 30. When revolved in one direction worm 14 coacts with the teeth of segmental gear 13 to angularly shift plate member 20 in an upward direction while when the head 15 is revolved in the opposite direction, worm 14 is turned to correspondingly engage the gear teeth of the segment 13 to shift plate member 20 in an angularly downward direction. This adjustment has the effect of angularly shifting the end of the magnetized core C with respect to the peripheral outline R' of the rotor R for precisely controlling the phase of the generated current.

The solenoid windings which coact with the adjustable magnetized core C are mounted on the plate 20. In Figs. 1, 2 and 3 I have shown a single electromagnetic winding S carried by the bobbin or coil support 31 with the ends of the winding extending through the cable represented at A. Suitable means of attachment, such as bracket 32, are provided for mounting solenoid S on plate member 20 intermediate the pivotal end thereof represented at 33 and the segmental gear end thereof represented at 13. The solenoid S has an axial passage extending therethrough to permit magnetized core C to be advanced or retracted with respect to the solenoid winding S under control of the micrometer screw 17 operating in the internal screw threads 18 of the transversely extending projection 19 of plate 20. The magnetized core C is controlled in longitudinal movement by the coaction of the calibrated cylindrical extension 11 on projection 19 and the coacting calibrated micrometer adjusting head 12. The combination of micrometer threads enables extremely minute movements to be imparted to the magnetized core C for selecting the air gap between the end of magnetized core C and the periphery of the rotor R with extreme precision. Thus the amplitude of the current generated in the winding of solenoid S can be changed by changing the air gap between the periphery of the rotor R and the end of the magnetized core C.

The combination movement thus provided by longitudinal adjustment of the magnetized core C and the angular adjustment of the magnetized core C with respect to the periphery of the shaped contour R' of the rotor R enables precise control of the current generated in solenoid winding S. To decrease the amplitude the gap between the end of magnetized core C and the periphery R' of rotor R is increased and to change the phase of the current in solenoid winding S the plate 20 is angularly shifted with sleeve 22 as a center.

The utilization circuit which is connected with solenoid winding S may have a variety of applications wherever current of precise amplitude and phase is required.

In Fig. 4 I have illustrated a modified form of the structure of my invention in which the magnetic micrometer movement is associated with an electrical device consisting of a solenoid winding B adjacent the solenoid winding A. In this arrangement the solenoid winding A is wound upon a coil form 34 while solenoid winding B is wound upon an immediately adjacent coil form

35. The solenoid winding B may be connected in the regenerative regulator circuit or in an exciter circuit by which the initial magnetic flux in the core C may be regulated. The separate 5 solenoid windings A and B which are associated with the same magnetized core C may be connected to separate electron tube circuits which are thus magnetically coupled through the adjustable magnetized core C as shown for example, in Fig. 5.

In the arrangement illustrated in Fig. 5 the solenoid winding A connects to the input circuit of an electron tube amplifier designated generally at 36, the output circuit of which, represented at 37, is coupled to a mixing circuit represented at 38. The adjacent solenoid winding B is connected to the input circuit of electron tube amplifier 39, the output circuit of which is represented at 40 coupled to the mixing circuit 38. Both the input and output circuits of the electron tube amplifier systems 36 and 39 are tuned so that the relatively feeble currents that are generated in the solenoid windings A and B may be built up to substantial amplitude at frequencies f_2 and f_3 by reason of the several tuned 15 circuits. The currents generated in solenoid windings A and B and delivered to mixing circuit 38 are controlled as to amplitude by the spatial relation of the end of magnetized core C with respect to the periphery R' of rotor R. These currents are controlled as to frequency by the speed of rotation of rotor R and as to phase by the angular position of magnetized core C with respect to the periphery R' of rotor R. By combining the outputs of the amplifier systems 36 and 39 in the mixing circuit 38 a resultant frequency f_4 is obtained which is of predetermined frequency, phase and amplitude. Any one of these factors may be selectively changed at will 20 by use of the magnetically adjustable system of my invention. To facilitate the comparison of this predetermined frequency, phase and amplitude current with an unknown source having comparable characteristics and which I have designated as f_1 the unknown source is picked up through the circuit designated at 41 and led through amplifier system 42 to the tuned circuit 43. The outputs of circuits 38 and 43 may 25 then be selectively impressed upon the coupling system 44 leading to the detector system 45 by operation of either switch 46 or 47. The detector 45 connects to the amplifier 48, the output of which connects to the cathode ray oscilloscope 49. Thus the wave trace of the energy delivered by the electric generator of my invention of the frequency f_4 may be observed when switch 46 is closed and switch 47 is open. Upon opening switch 46 and closing switch 47 the characteristics 30 of the source of unknown frequency f_1 may be observed. Upon closing both switches 46 and 47 the characteristics of both the locally generated frequency f_4 and the unknown frequency f_1 may be observed, studied and analyzed. In order 35 to determine the characteristics of the unknown frequency f_1 , the current delivered by the local generator may be adjusted according to the calibrations on motor controller D at 50 as to motor speed; according to calibrations 16 as to phase; and according to calibrations 51 of micrometer 11 according to amplitude so that there may be reproduced on the screen of the oscilloscope a wave trace represented at 52 which substantially corresponds with the wave trace of the unknown source represented at 53 for thus reproducing 40

and determining the characteristics of the unknown source.

As hereinafter stated the solenoid winding B may be regeneratively coupled through an electron tube system and through the magnetized core C with the solenoid winding A or solenoid winding B may be energized from a potential source 54 controlled through an adjustable rheostat 55 for establishing the initial magnetic flux in the magnetic core C as represented in Fig. 6. Thus a further precision control feature is added to the system of my invention by selectively controlling the magnetic saturation of the magnetized core C.

While I have described my invention in certain of its preferred embodiments and have mentioned certain applications thereof, I realize that structural changes may be made in the mechanism of my invention and that my invention may be applied to numerous applications. Accordingly, I intend no limitations or restrictions upon my invention other than may be imposed by the scope of the appended claims.

What I claim and desire to secure by Letters Patent of the United States is as follows:

1. In a multiple wave generator a supporting structure, a driving shaft journaled with respect to said supporting structure, a magnetic rotor driven by said shaft, a bracket mounted on said supporting structure and spaced from said driving shaft, a plate member journaled at one end about said shaft and projecting into said bracket at the other end thereof, adjustable gear means associated with the last mentioned end of said plate member, an electromagnetic solenoid system a bracket for mounting said electromagnetic solenoid system on said plate member, a magnetized core member adjustable through said solenoid system toward or away from the periphery of said magnetic rotor, an electrical circuit connected with said solenoid system, and means associated with said gear system for variably adjusting the spatial relation of said magnetized core member with respect to the periphery of said rotor and selectively fixing the radial position of said magnetized core member with respect to the periphery of said rotor for controlling the characteristics of current generated in said solenoid system and supplied to said electric circuit.

2. In a multiple wave generator comprising, in combination with a variable speed driving motor, a supporting structure, a driven shaft journaled with respect to said supporting structure and operated by said motor, a bracket mounted on said supporting structure and spaced from said driving shaft, a rotor of magnetic material carried by said shaft and having a pre-formed periphery shaped to produce pre-determined characteristics in the generation of electric current, an angularly adjustable member angularly shiftable about said driven shaft as a center and extending through said bracket, an electromagnetic winding carried by said angularly adjustable member, a magnetized core longitudinally adjustable through said electromagnetic winding toward or away from the periphery of said rotor, and screw devices disposed adjacent said bracket for adjusting both the radial position of said magnetized core and the spatial relation of the end of the magnetized core with respect to the periphery of said rotor.

3. In a multiple wave generator, a supporting structure, a magnetic inductor, a shaft journaled with respect to said supporting structure for ro-

tatively driving said inductor, a variable speed motor for driving said shaft, a bracket mounted on said supporting structure and spaced from said driving shaft, a solenoid system, a magnetized core adjustable through said solenoid system toward and away from the periphery of said rotor, and adjustable means disposed adjacent said bracket for controlling the air-gap between the end of said magnetized core and periphery of said rotor and controlling the radial position of said magnetized core with respect to the periphery of said rotor, and separate means for controlling the speed of said motor whereby said solenoid system effectively supplies electrical current, controllable as to phase, amplitude, and frequency.

4. In a multiple wave generator a supporting structure, a variable speed motor, a shaft driven by said motor, means for journaling said shaft with respect to said supporting structure, a hub-like projection on said means, a magnetic inductor carried by said shaft in a position beyond said hub-like projection, a bracket mounted on said supporting structure and spaced from said driving shaft, a plate member having one end thereof journalled on said hub-like member and having the other end thereof projecting through said bracket an adjustable screw means supported by said bracket and engaging the last mentioned end of said plate member for angularly shifting said plate member about said hub-like member as a center, a solenoid system carried by said plate member, a magnetized core extending through said solenoid system, directed toward the periphery of said magnetic inductor, and screw means disposed adjacent said bracket for advancing or retracting said magnetized core.

5. In a multiple wave generator a supporting structure, a variable speed motor, a shaft driven by said motor, means for journaling said shaft with respect to said supporting structure, a hub-like projection on said means, a magnetic inductor carried by said shaft in a position beyond said hub-like projection, a bracket mounted on said supporting structure and spaced from said driving shaft, a plate member having one end thereof journalled on said hub-like member and having the other end thereof projecting through said bracket, an adjustable screw means supported by said bracket and engaging the last mentioned end of said plate member for angularly shifting said plate member about said hub-like member as a center, a solenoid system carried by said plate member, a magnetized core extending through said solenoid system, directed toward the periphery of said magnetic inductor, screw means disposed adjacent said bracket for advancing or retracting said magnetized core, and calibrated means for selectively determining the air-gap between the end of said magnetized core and the periphery of said rotor, and the radial position thereof with respect to the periphery of said rotor.
